UNITED STATES PATENT OFFICE

2,445,123

CABLE GRAB BLOCK.

George Radde, Center Line, Mich.

Application February 22, 1943, Serial No. 476,789

7 Claims. (Cl. 24—133)

1

This invention relates to a grab block or clamping device for cables or the like and especially to an improved device adapted to grip a cable securely and tightly while avoiding any material danger of distorting, injuring or kinking the cable at the locality of the block. The device of the present invention is susceptible of a variety of uses, and may be employed to grip or clamp any type of cable or rope whether formed of wire strands or otherwise. One important use of the present grab block is in connection with stopping off a cable or line which has been made fast at opposite ends, permitting a straight line pull to be exerted through the block to the portion of the cable attached at its end to the object to be removed, the opposite end of the cable being released after applying the grab block. Many other uses of the device will be apparent, such as for gripping tow cables on barges or the like, bridge cables, hoisting cables, anchor cables, halyards, towing hawsers, and for various maritime purposes.

An object of the present invention is to provide an improved grab block or clamping device for cables or the like which will grip the cable firmly and securely without material injury or damage thereto.

A further object of the invention is to provide a device of the foregoing type having relatively movable cam operating members adapted to grip the cable over a considerable length thereof, thus eliminating excessive bite or tension at any localized area or point on the cable.

Another object of the invention is to provide an improved cable gripping or clamping device which will compensate automatically for any shrinkage in diameter of the cable under tension while avoiding any danger of sharp bends or kinks in the cable likely to damage the cable when heavy strain is placed thereon.

Still a further object of the invention is to provide an improved grab block or clamping device for cables or the like of sturdy, durable construction in which the cable is adapted to be gripped between generally concavo-convex gripping surfaces of relatively movable cam members, which surfaces are adapted to engage the cable smoothly and uniformly over a sufficient length of the cable to avoid excessive localized pressure points, and in which a substantially straight line pull through the device is possible without, however, weakening the cable, thus facilitating use of the device for a wide variety of purposes and especially where it is desired to stop off a cable which is fast or secured at both ends.

Another object of the invention is to provide an improved device of the foregoing type which is relatively simple and compact in construction, easy to manipulate and to apply to a cable to be

gripped, and which is efficient in use, while minimizing any material tendency to injure, weaken or damage the cable.

Other objects of this invention will appear in the following description and appended claims, reference being had to the accompanying drawings forming a part of this specification wherein like reference characters designate corresponding parts in the several views.

Fig. 1 is a side elevation illustrating a clamping device or grab block constructed in accordance with the invention, the parts in this view being illustrated in open position.

Fig. 2 is a fragmentary view, similar to Fig. 1 but illustrating the gate or latch member in closed position for confining the cable within the device.

Fig. 3 is a fragmentary view, somewhat similar to Fig. 1, illustrating the parts in closed operative position.

Fig. 4 is an enlarged section taken substantially through lines 4—4 of Fig. 3 looking in the direction of the arrows.

Fig. 5 is a plan view of the structure shown in Fig. 3.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the invention comprising a backing or supporting metal plate 10, a metallic face plate or front supporting plate 11, and an interposed metallic pressure plate 12. The plates 10, 11 and 12 are secured together by means of a shoulder rivet 13 which has a cylindrical bearing portion 13a upon which the intermediate pressure plate 12 is preferably pivoted for limited pivotal or swinging motion, as herein-after described.

The present device also comprises a cam lever or pressure member 14 which is mounted for pivotal or swinging motion upon the backing plate 10. As illustrated in Fig. 4, the cam lever 14 is rotatable upon a bearing sleeve 15 through which extends the shank of a rivet 16. Also mounted for pivotal or swinging motion upon the sleeve 15 is a latch or gate member 17 which in its closed position shown in Fig. 2 forms in effect a portion of the front supporting plate 11. From the construction shown in Fig. 4 it will be seen that the swinging lever 14 and latch or gate member 17 are secured to the backing plate 10 by means of the rivet 16, there being a friction

washer 16 between one head of the rivet and the face of the latch member 17, the construction being such as to permit the elements 14 and 17 to be swung on the sleeve 15 in the manner illustrated in Fig. 1.

The cam lever 14 is provided with a projecting arm 19, and to the outer end of this arm is pivoted a clevis 20 to which may be attached one end of a cable 21. The cam lever 14, at its opposite side from the arm 19, has an enlarged cam portion provided with a peripheral arcuate groove 22 which extends the full length of the cam portion. The groove 22 provides a cable engaging surface which is convex and curvilinear in shape. The pressure plate 12 is also provided with an arcuate cable engaging groove 23, this groove being formed on the inner edge of the plate 12 and providing a curvilinear generally concave surface cooperable with the convex grooved surface 22 to embrace the cable to be gripped. It will be seen that the backing plate 10 extends a distance beyond the grooved edge 23 of the pressure plate 12, and in like manner the face plate 11 is extended at 11a beyond this groove. Thus, the plates 10 and 11 form a channel, the base of which is formed by the groove 23.

The latch or gate member 17 has a projecting latch portion 17a adapted to fit into a recess 24 in the portion 11a of the face plate. When the member 17 is in closed position as shown in Fig. 2, the arcuate edge 17b of this member fits smoothly against the edge 24a of the face plate. This edge is preferably grooved so that the rounded edge 17b will fit thereto when the member 17 is closed. Similarly the ribbed edge 24b of the plate 11 cooperates with a grooved edge of the patch 17.

The pressure member 12 is preferably made separate from the supporting plates 10 and 11 so as to permit it to be mounted for limited movement about the pivot 13. However, if desired, the member 12 may be made integral with the plates 10 and 11 or may be secured rigidly thereto. In the present instance, the pressure member 12 has an arcuate slot 25 through which extends a rivet 26. With this construction the member 12 may swing about the pivot 13 a distance limited by the length of the lost motion slot 25.

Figs. 1, 2 and 3 illustrate in successive steps the manner in which a cable 27 may be stopped off or gripped intermediate its ends. The arm 19 is swung counter-clockwise so as to lift the cam portion of the lever out of the channel between the supporting plates 10 and 11, and the latch or gate member 17 is swung outwardly, the position of the parts after the foregoing operation being shown in Fig. 1. When the latch or gate member 17 is lifted to its position of Fig. 1 a slot is opened into the side of the channel formed between the plates 10 and 11. This slot is formed above the edges 24a and 24b of the member 11 which is thus cut off short of the outer end of the backing plate 10. With the parts in this position the cable 27 may be passed bodily through the slot, as shown in dotted lines in Fig. 1, and thence shifted into the channel between plates 10 and 11 as shown in full lines in Fig. 1. Thereupon the latch or gate member 17 is closed, as shown in Fig. 2, thereby confining the cable within the channel so that it cannot be removed therefrom. In the next operation the handle 19 is grasped to swing the cam lever in a clockwise direction to force the cable 27 into the groove 23 of the pressure plate 12. The cable is thus cammed smoothly into the base of the channel

and gripped between the grooved edges 22 and 23 of the cam or pressure members. As seen in Fig. 3, the groove 23 continues outwardly beyond the cam member 14 on a reverse curve 23a over the upper nose of the pressure member 12 and thence the portion 27a of the cable is extended to an object to which its end is attached. The opposite portion 27b of the cable extends to a second object to which its end is attached. When the cam member 14 is shifted into the position shown in Fig. 3 to grip the cable against the member 12, the latter may move a limited amount under the pressure of the member 14 so as to accommodate, for example, variations in the diameter of the cable, permitting a smooth uniform engagement of the cable throughout the length of the groove 22.

It will be noted that the front plate 11 and the gate piece 17, when connected as in Fig. 3, act as a unitary plate and cooperate with the back plate 10 in transmitting any stress caused by the pressure of the cable 27 on the pressure member 14. It will be observed, in connection with the particular embodiment herein illustrated, that when a pull to the left is exerted on cable portion 27a, see Fig. 3, this force will be greater than the opposing force caused by the friction between the pressure plate 12 and the pressure member 14, thus producing a force tending to cause the cable to slide to the left between the cable-engaging surfaces of the plate 12 and the member 14. However, the pressure member 14 has a cable-engaging surface of varying radius; so that a clockwise rotation of the member 14 causes a gripping action on the cable 27 between the plate 12 and the member 14 which causes a gripping pressure and resultant friction which is greater than the force tending to slide the cable to the left. The rotating force on arm 19 is produced by reason of the fact that the pivot 16 lies below the straight line connecting cable portion 27a and cable 21 when the cable 27 is in place between members 12 and 14 as illustrated in Fig. 3. The pull exerted on arm 19 in the direction of the arrows in Fig. 3 is transmitted uniformly to the front and back plates 11 and 10. The portion of this pull or force taken by plate 11 is transmitted thereto by gate piece 17 through the interfitting portions 17a and 24c, and hence when the grab block is under tension the gate piece will be held tightly in place against release.

I claim:

1. A clamping device for cables or the like comprising a support having spaced substantially parallel side members, a cam lever pivotally mounted between said members and shiftable therebetween to grip a cable between curved clamping surfaces on the lever and support, one of said side members comprising a part attached to the other side member and a second part swingable relatively to said first part to form between said parts an opening through which a portion of the cable between its ends may be inserted bodily into the space between said members.

2. A clamping device for cables or the like comprising a support having spaced substantially parallel side members, a cam lever pivotally mounted between said members and shiftable therebetween to grip a cable between curved clamping surfaces on the lever and support, one of said side members comprising a part attached to the other side member and a second part shiftable relatively to said first part to form between said parts an opening through which a portion of the cable between

its ends may be inserted bodily into the space between said members, said part and cam lever having a common pivotal mounting.

3. A clamping device for cables or the like comprising a support having spaced substantially parallel side members, a cam lever pivotally mounted between said members and shiftable therebetween to grip a cable between curved clamping surfaces on the lever and support, one of said side members comprising a part attached to the other side member and a second part swingable in the plane of the first part to form between adjacent edges of said parts an opening through which a portion of the cable between its ends may be inserted bodily into the space between said members, said second part when swung into position to close said opening having an interlocking connection with said first named part.

4. In a device for gripping a cable or the like, a support comprising a base having front and back walls projecting therefrom and spaced apart to provide a channel, said base being formed at the bottom of the channel between said walls with a curvilinear cable clamping groove to receive the cable with the cable confined between said walls, one of said walls comprising a portion fixed to the other wall and a second portion swingable to form with said first portion an opening to permit a portion of the cable between the ends thereof to be inserted through the opening into the channel, and a clamping member pivoted to the support and shiftable into position within the channel to clamp the cable in said groove, said second named portion being shiftable into position to close said opening.

5. In a device for gripping a cable or the like, a support comprising two spaced substantially parallel walls forming a channel therebetween and terminating at their inner edges in a curvilinear base portion closing the bottom of the channel and formed with a cable clamping surface, a clamping member pivoted to the outer end portions of said walls and lying therebetween so as to swing into and out of the channel to grip the cable against said surface along the bottom of the channel, one of said walls comprising a portion fixed to the other wall and an outer end portion swingable about the pivotal axis of said clamping member into position to permit a portion of the cable between its ends to be bodily passed between the portions of said one wall into the channel.

6. In a device for gripping a cable or the like, a support comprising two spaced substantially

parallel walls forming a channel therebetween and terminating at their inner edges in a curvilinear base portion closing the bottom of the channel and formed with a cable clamping surface, a clamping member pivoted to the outer end portions of said walls and lying therebetween so as to swing into and out of the channel to grip the cable against said surface along the bottom of the channel, one of said walls comprising a portion fixed to the other wall and an outer end portion swingable about the pivotal axis of said clamping member into position to permit a portion of the cable between its ends to be bodily passed between the portions of said one wall into the channel, and an interlocking connection between said last named wall portions.

7. In a device for gripping a cable or the like, a support comprising two spaced substantially parallel walls forming a channel therebetween and terminating at their inner edges in a curvilinear base portion closing the bottom of the channel and formed with a cable clamping surface, a clamping member pivoted to the outer ends of said walls and lying therebetween so as to swing into and out of the channel to grip the cable against said surface along the bottom of the channel, one of said walls including a part fixed to the other wall and an outer end part coplanar with said fixed part and swingable relatively thereto, the swingable part having an interlocking connection with the fixed part to provide substantially a continuous wall and also adapted to be swung away from the fixed part to provide therewith a gap in the wall through which a portion of the cable between its ends may be bodily inserted into the channel.
